United States Patent Office

Des. 208,520
Patented Sept. 5, 1967

208,520

TENT

Andro J. Chorey, 8315 Gibson Road,
Canfield, Ohio 44406

Filed June 29, 1966, Ser. No. 2,859

Term of patent 14 years

(Cl. D88—3)

FIG. 1.

FIG. 2.

FIG. 3

FIG. 4.

FIGURES 2, 3 and 4 are end, top and side views, respectively, of the tent.

The dominant features of my design are shown in full lines in the drawings. Portions of the fabric have been indicated fragmentarily for convenience of illustration.

I claim:

The ornamental design for a tent, substantially as shown and described.
